UNITED STATES PATENT OFFICE.

ERNEST E. HEINTZ, OF DETROIT, MICHIGAN, ASSIGNOR TO TERNSTEDT MANUFACTURING COMPANY, OF DETROIT, MICHIGAN, A CORPORATION OF MICHIGAN.

TORSION-SPRING TENSION REGULATOR.

Application filed November 20, 1922. Serial No. 602,300.

To all whom it may concern:

Be it known that I, ERNEST E. HEINTZ, a citizen of the United States, residing at Detroit, in the county of Wayne and State of Michigan, have invented certain new and useful Improvements in Torsion-Spring Tension Regulators, of which the following is a specification.

This invention relates to tension regulators for torsion springs and has for its object a very simple device which holds the spindle in any one of an infinite number of varying positions of tension. Its chief recommendation is that any degree of tension may be attained and its simplicity makes its cost only nominal.

The device was originally invented for the purpose of governing the tensioning of a counterbalancing spring of a window regulator, but it will be apparent that it has a wide applicability and it can be used on curtain rollers and any other place where a torsion spring and a spindle is used.

In the drawings:

Fig. 1 is a side elevation of a novel form of window regulator on which the tension regulating device is used.

Fig. 2 is a horizontal section of the barrel or drum on which the cable winds.

Figs. 3 to 6 inclusive, are cross sections taken on the similarly numbered section lines of Fig. 2.

Fig. 7 is a detail of one end of the drum supporting bracket, showing the tension regulating spring.

No claim is made for the regulator in this application. It may be described in general terms as a frame *a*, on which is supported the pulley wheel *b*, over which runs the cable *c* provided with a connection *d* with the lower rail *e* of the vertically sliding window *f*. The upper end of the cable winds at *g* over a drum or barrel *h*; the two ends of the cable being fastened at *j* and *i* on the barrel so that as the barrel rotates one portion of the cable unwinds and the other portion of the cable winds up.

Window regulators are customarily provided with a counterbalancing spring, that is, a spring which winds up when the window travels down and furnishes helpful energy when the window is raised. This tends to make the turning effort in either direction nearly equal. In the type of window regulator here shown, the counterbal-

ancing spring *k* is very similar to a curtain roller spring, in fact, the drum *h* is quite like a curtain roller. The spring at one end is anchored as at *m* on the spindle *n*, and at the other end anchored as at *o* in the drum. Now obviously, by altering the angular position of the spindle *n*, the tensioning of the counterbalancing spring may be regulated to be nicely adjusted to the weight of the glass. This is desirable in window regulator construction.

This I accomplish by an unusually simple expedient. The bracket *p* and *p'* supports the spindle rotatably; over one end of the spindle I fit the coiled spring *q*—the coils have to be spread slightly in order to be fitted onto the spindle. One end *r* is anchored in a suitable perforation in the bracket *p* and the other end *s* is free. When it is desired to lessen the tension on the counterbalancing spring, a tool *t* is pressed against the free end *s* of the spring to slightly open the coils. This permits the spindle to turn in the coils under the turning effort of the counterbalancing spring. This immediately relieves the tension. Only a slight effort is necessary on the tool to start the release of the tension, and of course must be immediately discontinued or else the spring will completely unwind. When it is desired to increase the tension on the counterbalancing spring, one simply seizes the end of the spindle with a pair of pliers or other suitable tool and turns it counterclockwise as shown by the arrow in Fig. 7. This turning effort in itself tends to open up the coils in the spring *q* and hence releases the grip during the winding up operation. As soon as this turning effort is released the counterbalancing spring exercises a turning effort in the opposite direction, which tends to close the coils of the spring *q* and grips tightly about the spindle. This prevents any slippage.

What I claim is:

1. In a device of the kind specified, the combination of a torsion spring and a cylindrically surfaced anchor for one end of the torsion spring, said anchor supported for angular movement when released and a tension regulator therefor, comprising a coiled spring, engaging the cylindrical surface thereof and arranged so that the turning effort of the torsion spring tends to cause the coils to grip said surface and prevent the

turning of the anchor, but which permits turning effort exercised directly on the anchor for the purpose of increasing the tension on the torsion spring to release the grip 5 of the coil spring and permit such angular movement.

2. In a device for the purpose specified, the combination of a torsion spring and an anchor for one end thereof mounted to turn 10 when released, and a coiled spring arranged to grip said anchor when turning effort is exercised on the anchor by the torsion spring, but permitting turning movement exercised directly on the anchor to increase 15 the tension of the coiled spring.

3. In a tension device for the purpose

specified, the combination of a torsion spring, a spindle to one end of which said spring is anchored, and a coiled spring having one end anchored and said spring coiled about 20 the spindle tightly so that turning effort exercised on the spindle through the tension spring tends to hold the spindle in a given position of adjustment, while the adjustment may be altered to increase the torsion 25 spring tension by simply turning the spindle and may be altered to lessen the tension on the torsion spring by opening up the coils of the spring.

In testimony whereof I affix my signature:

ERNEST E. HEINTZ.
